D. S. HARTSHORN,
CONTAINER.
FILED Oct. 20, 1921.

Inventor
DERICK S. HARTSHORN

Ch. Parker

Attorney

UNITED STATES PATENT OFFICE.

DERICK SIBLEY HARTSHORN, OF WILLIAMSPORT, PENNSYLVANIA.

CONTAINER.

Application filed October 20, 1921. Serial No. 509,017.

To all whom it may concern:

Be it known that I, DERICK S. HARTSHORN, a citizen of the United States, residing at Williamsport, in the county of Lycoming and State of Pennsylvania, have invented 5 certain new and useful Improvements in Containers, of which the following is a specification.

This invention relates to means for securing corners, tops or bottoms on receptacles, of which boxes, chests, drawers, crates and trunks are common examples. It comprises suitable sides and ends with a reinforcing binding strip of substantially U section covering and protecting the ends of material, of 10 which the container is made; said reinforcing strip being provided with alternate spaces and teeth, the teeth of one member fitting into the spaces of the adjacent member and being held in correct relative position by a pin or rod passing through the interlocked sections.

In connection with the foregoing, I preferably employ plates or angles through 25 which the rods pass, to fasten the top and bottom of the box in position.

An object of the invention is the reinforcement of the material from which the body of the container is made, such as preventing 30 wood from splitting, or paper or fibre from tearing.

In addition to this, I have an excellent means for fastening the corners together by the interlocking reinforcing strips.

35 A further object of the invention is the provision of a container which may be used as a box for shipping, and which permits the box to be collapsed when emptied and returned to sender, saving space and cost in shipping.

A further advantage of the invention is the provision of a box, having parts of standard size, whereby a broken part may be replaced without the necessity of discarding 45 the whole box.

To illustrate my invention, I have chosen a box which shows the novel features, several embodiments of which are shown in the accompanying drawing.

50 Figure 1 is a perspective view of the box assembled,

Figure 2 is a vertical sectional view on line 2—2 of Figure 1,

Figure 3 is a detailed view showing modified type of fastening means,

Figure 4 is a perspective view of the parts in position for assembling, and,

Figure 5 is a horizontal sectional view of one of the corners of the box.

Referring to the drawings, the reference 60 numeral 1 designates side walls and 2 the end walls of the box. The edges of the side and end walls are provided with substantially U-shaped reinforcing members 3. As shown, these reinforcing members are arranged on opposite sides of the box member and project beyond the edge. They may be secured to a box by any suitable fastening elements 4. The reinforcing members are provided with spaced notches 5 separated by 65 sections 6. When the box is assembled (see Figures 3 and 5) the sections 6 of one reinforcing element are received in the notches 5 of the adjacent member forming an interlocking joint. A pin 7 is passed through the 70 reinforcing elements to retain the parts in assembled position.

The box is further provided with a top 8 and a bottom 9 and these parts are retained in position by means of angle plates 10 arranged at opposite ends of the box. As 80 shown, the plates are provided with openings 11 for the reception of the pin or fastening member 7.

In Figures 1 and 2 of the drawing, I have 85 shown a fastening element provided with heads 12 formed thereon in any suitable manner, as by swaging.

In Figure 3 of the drawings, I have shown a fastening element provided with one enlarged head 12 and threaded at the opposite 90 end for the reception of a nut 13. By providing a pin having a threaded end the nut may be removed when the box is to be disassembled.

95 It will be apparent that the interlocking corner pieces provide a box of maximum strength, the side and end walls being reinforced by the metallic reinforcing members which prevent the walls from splitting. The 100 box may be quickly assembled and disassembled permitting it to be returned to the sender at a great reduction in cost.

The parts employed are interchangeable which permits a broken part to be replaced 105 without discarding the whole box.

It is to be understood that the form of my invention herewith shown and described is to be taken as a preferred example of the same, and that various changes in the shape, 110

size, and arrangement of parts may be resorted to without departing from the spirit of the invention or the scope of the subjoined claims.

5 Having thus described my invention, I claim:

1. A container comprising side and end sections, the ends of said sections being provided with interlocking reinforcing members, a top and bottom for said container, plates arranged on said end sections to retain top and bottom in position and fastening members engaging said plates and said interlocking reinforcing members.
- 10 2. A container consisting of side and end sections and a top and bottom, plates arranged on said top and bottom, and connecting members passing through said container and through said plates to hold them in their respective places.
- 15 3. A container consisting of side and end sections and a bottom, reinforcing strips arranged across the bottom of the container, and connecting members passing through said strips and through said side and end sections to hold said strips in position.
- 20 4. A collapsible box comprising side and

end sections, substantially U shaped reinforcing members secured to the ends of said sections and projecting therefrom, said reinforcing members being provided with spaced notches adapted to receive portions of the adjacent reinforcing members, angle plates arranged on said end sections, a top and bottom for said box, said angle plates being adapted to retain said top and bottom in position, and pins extending through said angle plates and through the interlocked portions of said reinforcing members.

5. A collapsible box comprising side and end sections, the ends of said sections being provided with interlocking reinforcing members, a bottom for said box, angle plates arranged on said end sections to retain the bottom in position, and fastening members engaging said angle plates and said interlocking reinforcing members.

In testimony whereof I affix my signature in presence of two witnesses.

DERICK SIBLEY HARTSHORN.
